SELF-WRINGING MOP

Floyd H. Harris, Cincinnati, Ohio, assignor to Bromo-Mint Company, Cincinnati, Ohio, a corporation of Ohio

Application October 19, 1956, Serial No. 191,009

4 Claims. (Cl. 15—119)

This invention relates to mops having a single swab element and is particularly directed to a novel type of self-wringing mop in which the swab is effectively and uniformly compressed by a wringing mechanism which can be actuated from a point on the mop handle remote from the swab end.

Mops of the type to which this invention relates are used to clean such surfaces as tile, asphalt and linoleum floors, walls and the like. Preparatory to the actual mopping, the swab element, comprising a cellulosic sponge or some similar absorbent substance, is immersed in a bucket of water containing a solution of soap or detergent. After the swab element has absorbed a quantity of water, the mop is withdrawn from the bucket and is either applied directly to the surface to be cleaned or is first conditioned for use by forcing some of the water out of the porous sponge to avoid applying an excessive amount of water to the floor or wall being cleaned.

After the dirt has been loosened and picked up by the sponge, the swab element is squeezed over a bucket or drain so that the water contained in its pores is forced out leaving the sponge in a condition in which it may be used to absorb and remove any water remaining on the floor. After the swab element has absorbed a quantity of the excess water from the floor or wall, it is again squeezed out; and the operation is repeated as often as necessary.

The water used is often very warm, perhaps even boiling, and the soap or detergent is likely to be rather strong. Furthermore, it is obvious that in the process of mopping even a relatively small area, it is necessary to wring out the mop a large number of times. As a result, it is very desirable to provide a means for squeezing the excess moisture from the swab element which does not require the operator's hands to come into contact with those portions of the mop which have been immersed in cleaning solution. Convenience makes it further desirable that the squeezing means be associated with the mop rather than a separate unit secured to the bucket or placed near the drain.

A variety of devices have been developed which permit the swab element to be squeezed by a wringing mechanism carried by the mop. While these wringing mechanisms have been more or less effective, none has been entirely free of serious defects in one respect or another. Those types which employ a divided swabbing element require that a considerable amount of space be left between the hinged elements thus making the mop head large and unwieldy. Other devices employ a single swab element, but the squeezing action provided is such that the swab element is subjected to definite shearing and tearing stresses. Other proposed mechanisms do not effect a thorough squeezing of the entire swab; that is, portions of the sponge will be squeezed so that almost their entire amount of moisture is forced out while other portions are subject to very little compression and hence are left with most of the water still retained in their pores. Others do not have a wringer attachment that is compact enough to drain into the average-size pail, as

2

the swab is being wrung, and also of a size which can be dipped into such a pail in a non-wringing condition.

Another common fault with self-wringing mops has been that the wringing mechanisms are often manipulated by handling a rod or some similar means located near the swab end. While these means do not require touching the swab proper, they do entail a handling of other portions at the wet end of the mop and hence a large part of the advantage secured by providing a wringing mechanism is lost.

The present invention, which avoids these difficulties, proposes a novel sponge mounting and linkage by means of which the sponge may be effectively and uniformly squeezed to discharge moisture retained within the sponge cells.

One feature of this invention is a positive locking arrangement to keep the swab-sponge head compressed in its wringing position until it is desired to release it from such position. In other words, I have provided a mop 20 in which a constant squeezing pressure may be maintained on the swab without a corresponding, continuing pressure on the part of the operator. Additionally, by this structure, the pressure which need be executed by the operator in expelling water from the mop is minimized. In 25 fact, the arrangement of this invention translates a simple pulling motion into a compression effective to wring the swab to a low moisture content.

These advantages are accomplished, in part, by the 30 concept of having two entirely different and distinct positions for the mop head in its respective mopping and wringing operations. Both the mopping position and the squeezing-wringing position are stable ones. In the mopping position the swab is angulated with respect to the 35 mop handle so that it will ride on the floor when the conventional mopping stroke is employed. On the other hand, when it is desired to expel water from the swab, it may be retracted from this mopping position into a wringing position in which the swab head is in facial abutment and pressure contact with a squeeze surface. 40 Compressed between a backing plate and this squeeze surface, the swab loses its excess water and is ready for reuse.

Adjustment from one of these positions to the other 45 is made by manipulations remote from the wet end of the mop. For that purpose, I here disclose structure for actuating the wringing or squeezing mechanism of the mop which includes a movable sleeve mounted on the mop handle at a point removed from the swab end. Thus, by sliding the sleeve with one hand while holding 50 the mop at its free end with the other, the operator can squeeze the swab without contacting either the swab or the wet and soiled parts associated with it.

I am aware that it has been previously proposed to 55 utilize a sleeve arrangement in which a wringing action is exerted on the swab at the end of a downward "push" stroke of the sleeve. In order to present a graspable surface on the handles of such mops, however, those sleeves have been normally positioned below that portion of the stick which is held during the mopping stroke. 60 Thus, in order to actuate the sleeve and its corresponding wringing mechanism, it has been necessary either for the operator to bend over or to lift the mop well above the floor to push the sleeve downwardly along the handle. On the other hand, by employing my retraction principle, 65 the sleeve can be so situated on the mop stick that it is drawn over that part of the stick which is normally held by the hands. Thus, my mop can be held directly over a drain during the squeezing operation without the user's stooping or bending from an upright position, or without any significant movement from the mopping position.

After the water has been forced from the cells of the 70 sponge block and it is desired to return the block to the

angulated position in which it is held during mopping, the sleeve is moved along the handle away from the operator, or toward the swab end of the mop, the actuating rod forcing the hinge portion of the plates along an arcuate path towards the mopping position. When the sleeve has reached its position of maximum travel, it is locked in place by some catch means and the linkage constrains the backing plate at an operable mopping angle with respect to the handle while the squeeze plate is firmly held in an out-of-the-way floor clearing position.

An object of this invention, therefore, is to provide a mop in which the swab element may be squeezed free of water without the necessity of the operator touching any part of the wet, soapy end of the mop.

Another object of this invention is to provide in a self-wringing mop a means for effecting a uniform compression of the swab element.

An additional object of this invention is to provide in a self-wringing mop, actuating means for the wringing mechanism which do not require that the operator's hands be changed from their normal mopping position.

A further object of this invention is to provide a squeezing mechanism which will function without subjecting the swab element to any appreciable shearing stress.

An additional object of this invention is to provide a squeeze plate which is so mounted that it is positively held in an out-of-the-way floor-clearing position during the period when the mop is being pushed across the surface being cleaned.

These and other objects and advantages of my invention will be apparent from a consideration of the specification in conjunction with the drawings in which:

Figure 1 is a front elevational view of the mop with the squeeze plate and backing plate disposed in the mopping position.

Figure 2 is a side elevational view of the mop with the backing plate and squeeze plate in the mopping position.

Figure 3 is a side elevational view of the mop, partially broken away to show details of the linkage actuating the backing and squeeze plates, which are shown in the mopping position.

Figure 4 is a view similar to Figure 3 with the base plate and squeeze plate brought together into a parallel relationship to exert a compressive wringing action on the sponge.

Figure 5 is a diagrammatic side view of the mop in the mopping position.

Figure 6 is a view similar to Figure 5 showing the action of the actuating rod during the first part of its movement outwardly along the handle.

Figure 7 is a view similar to Figure 5 showing the action of the linkage at the commencement of the wringing action.

Figure 8 is a view similar to Figure 5 showing the squeezing and backing plates in the wringing position.

Figure 9 is a cross sectional view along line 9-9 of Figure 1.

Figure 10 is a cross sectional view along line 10-10 of Figure 3.

As disclosed in the drawings, I provide at the end of the mop handle two rotatable plates hinged together for pivotal movement relative to each other. One of the plates carries a cellulosic sponge block and the second, or squeezing plate, cooperates with this sponge backing plate to exert a wringing action on the sponge when the plates are moved into a squeezing position. Neither the backing plate nor the squeezing plate is fixedly mounted, both being pivotally mounted upon link members which themselves are rotatably supported by the mop handle. The hinge portion of the two plates is likewise movable, being drawn along a defined path by its actuating rod which is moved by, and attached to, the sleeve.

When the sleeve is pulled along the handle toward the

operator, the linkage is such that the two plates are brought into a parallel position, with the swab block being squeezed between them. The action of the plates in moving into their parallel squeezing relationship is such that the sponge is not only uniformly compressed but is subjected to practically no shearing stress which would have a tendency to tear or rip the cellulosic block.

Referring now to the figures in detail, the mop generally comprises a handle 10, a backing plate 11 carried thereby, a swab element 12 removably secured to plate 11, and a squeeze plate 13 hingeably connected to the backing plate 11 and adapted to cooperate with it to compress swab element 12 between them. A hand-convertible sleeve 14 is slidably mounted upon handle 10 remote from the swab end. Connecting sleeve 14 and the hinged portion of the squeeze and backing plates is an actuating rod 15 which transforms the linear movement of sleeve 14 into an arcuate movement of hinge 16 to guide the plates into and out of swab-squeezing position.

As shown in Figure 2, the handle 10 is provided with a spring-loaded depressible pin 17 which is adapted to cooperate with an aperture 18 in sleeve 14 to hold the sleeve and actuating rod in a fixed mopping position. A collar 20 is secured to the end of the mop and a channel-shaped hinge member 21 is rotatably secured to collar 20 as by a rivet 22. An end of hinge member 21 is pivotally joined to flanges 23 provided on the rear face of backing plate 11.

Backing plate 11 carries swab 12 which consists of a cellulose sponge or some similar material in the form of a rectangular block. As shown in Figure 9, sponge block 24 is joined to a backing strip 25 by any one of the adhesives well known in the art, and this backing strip is then covered with a sheet of cloth 26 which is also cemented to the sponge. Backing strip 25 is provided with apertures adapted to engage bolts 27 which pass through openings provided in the backing plate 11, thus effecting a firm but readily releasable juncture of plate 11 and swab element 12. It will be understood that the exact method of joining the backing plate and sponge constitutes no part of the present invention and that various methods of securing the two are contemplated.

Both backing plate 11 and squeeze plate 13 are provided with a plurality of flanges 28 having hinge pin receiving apertures 30 formed adjacent their outer edges. A hinge pin 31 is journaled in these apertures forming a hinged connection between the two plates. Squeeze plate 13 is further provided with a plurality of spaced openings 32 through which water can escape when the plates compress the sponge 24, thereby facilitating the removal of moisture from the sponge when the plates are brought into the squeezing position.

The linkage by which squeeze plate 13 is secured to handle 10 comprises a rotatable link 33 and a slide link 34. One end of each of the links 33 and 34 is disposed within a slot formed in the mop handle, as particularly shown in Figures 1, 3, and 4. Rotatable link 33 is mounted upon a pivot pin 35, provided in the mop handle, and is also pivotally secured to a pin 36 carried by flanges 37 of the rear surface of squeeze plate 13. Slide link 34 is joined by means of pin 38 to rotatable link 33 at a position near its center. Link 34 is provided with a slot 40 engaging a stop pin 41 which passes through the mop handle 10. The chief function of slide link 34 is to limit the travel of rotating link 33 in a manner to be later described.

Actuating rod 15, one end of which is secured to sleeve 14, is provided with an opening 42 adjacent its opposite end through which hinge pin 31, securing the backing and the squeeze plates together, is journaled. This permits the motion of sleeve 14 to be transmitted to the hinged portion of the squeeze and backing plates.

In operation, when it is desired to alter the relationship of the plates from their distended, or mopping, position to a juxtaposed, parallel squeezing position depress-

ible pin 17 is pushed downwardly freeing sleeve 14 to permit it to be pulled outwardly along mop handle 10. This action of sleeve 14 is transmitted to actuating rod 15, in turn drawing hinge pin 31 joining the backing and squeeze plates along an arcuate path. This path is first directed transverse of, and toward, the mop handle axis, then substantially parallel to it and finally transverse, and away from, the handle axis. As hinge pin 31 is moved by actuating rod 15, channel-shaped hinge member 21 rotates about pin 22, which joins it to collar 20. 10 This action is best illustrated in Figures 7 and 8.

As sleeve 14 and actuating rod 15 continue to move toward the free end of the mop handle, the arcuate path along which hinge 16 is proceeding is defined transversely but away from the axis of the mop handle. As hinge 16 is being moved parallel to the handle axis, rotatable link 33 has rotated about pin 35, which joins it with handle 10, to its most outward position. Further rotation of this link 33 is prevented by the engagement of the end of slot 40 of sliding link 34 with stop pin 41. 20 Meanwhile, the movement of hinge 16 forces the rotation of channel hinge member 21 until point 23 of its jointure with backing plate 11 is approximately aligned with its support point 22 on collar 20 and the end of rotatable link 33 secured to squeeze plate 13. In this position the squeeze and backing plates are converged into a juxtaposed, parallel relationship in which swab element 12 is compressed between them.

When it is desired to return the plates to their mopping position, sleeve 14 is slid along the mop handle 10 toward the swab end and the corresponding movement of rod 15 forces hinge 16 first toward the mop handle, and then parallel to it, causing channel hinge member 21 to rotate about its pivot point 22 on collar 20 and also causing rotatable link 33 to rotate toward mop handle 10. Further movement of the sleeve 14 results in actuating rod 15 forcing hinge 16 further along the handle and then outwardly from it.

At the end of the sleeve's travel, it is locked in place by the engagement of spring-urged pin 17 with sleeve opening 18. Thus, sleeve 14 and actuating rod 15 are firmly held in the mopping position against accidental disengagement. In this position, rotatable link 33 has rotated as far toward a parallel relationship with handle 10 as is permitted by the action of sliding link 34. That is, as the mopping position is approached, slot 40 in sliding link 34 engages stop pin 41 in the mop handle, thus preventing further movement of link 34 and hence preventing further rotation of rotatable link 33.

Additionally, pin 38, which joins slideable link 34 and rotatable link 33, is elongated so that it engages actuating rod 15 to prevent any further angular movement of rod 15 away from mop handle 10. This prevents alignment of the point of juncture of sleeve 14 and actuating rod 15, pivot point 36 of squeeze plate 13 and rotatable link 33, and journal 42 joining hinge pin 31 and rod 15. Obviously, if these three points were allowed to come into alignment the linear motion of sleeve 14 would not then cause hinge 16 to rotate about pivot point 36 (between squeeze plate 13 and rotatable link 33) and hence any movement of sleeve 14 would be ineffective to bring the plates into a parallel relationship.

It will be noted that in the mopping position, backing plate 11 is firmly held in an angulated position relative to mop handle 10 whereby swab 12 is advantageously disposed for its movement over the surface being cleaned. Furthermore, squeeze plate 13 is held in a floor-clearing, out-of-the-way position so that it will not interfere with the swab element.

It can be seen that a device constructed in accordance with my invention provides a simple but effective method of wringing moisture from a swab at the end of a mop stick. Furthermore, it will be noted that since the squeezing and backing plates are brought into an absolutely parallel relationship, the compression of the swab ele-

ment is uniform. And finally, it will be seen that the compressive action exerted upon the swab element is such that there are no shearing stresses set up in the sponge which would tend to shorten its life by tearing or ripping.

Having described my invention, I claim:

1. In a self-wringing mop having a handle and a swab mounted on said handle, the combination of a squeeze plate and linkage for positioning said plate relative said swab, said linkage comprising a rotatable link having one end thereof secured to said plate and the other end thereof secured to said handle and a second link pivotally joined to said rotatable link at an intermediate point thereof, said second link being slidably mounted for transverse movement relative said handle.

2. In a self-wringing mop having a handle and a swab mounted on said handle, the combination of a squeeze plate; linkage for positioning said plate relative said swab, said linkage comprising a rotatable link having one end thereof secured to said plate and the other end thereof to said handle and a second link pivotally joined to said rotatable link at an intermediate portion thereof, said second link being slidably mounted for transverse movement relative said handle; and means for limiting the sliding movement of said second link.

3. A self-wringing mop comprising a handle, a swab assembly, means for disposing said swab assembly at a plurality of angles with respect to said handle, said means including an elongate hinge member having its ends

30 rotatably secured to said handle and to said swab assembly respectively and configurated to reside in alignment with said handle, a squeeze plate, a hinge joining said plate to said swab assembly, a rod attached to said hinge and secured to said handle for longitudinal movement therewith, and linkage for positioning said squeeze plate relative said swab assembly, said linkage comprising a rotatable link having one end thereof secured to said plate and the other end thereof secured to said handle and a second link pivotally joined to said rotatable link at an intermediate point thereof, said second link being slidably mounted for transverse movement relative said handle.

4. A self-wringing mop comprising a handle, a swab assembly rotatably mounted thereon, a squeeze plate, linkage for positioning said plate relative said swab assembly, said linkage comprising a rotatable link having one end thereof secured to said plate and the other end thereof secured to said handle and a second link having one end pivotally joined to said rotatable link at an intermediate point thereof and having its other end movably mounted in said handle for limited slideable movement transversely thereof, a hinge connecting said swab assembly and said squeeze plate, a hand-contactible element slidably engaging said handle, and a link joining said hinge to said hand-contactible element for transmitting movement of said element into divergence and convergence of said swab assembly and said squeeze plate.
